UNITED STATES PATENT OFFICE.

HERMAN GILLIAN, OF TOLEDO, OHIO, ASSIGNOR OF ONE-HALF TO ARTHUR E. BACON,
OF TOLEDO, OHIO.

GLOVE.

Application filed May 18, 1923. Serial No. 639,762.

To all whom it may concern:

Be it known that I, HERMAN GILLIAN, a citizen of the United States of America, residing at Toledo, Lucas County, Ohio, have 5 invented new and useful Gloves, of which the following is a specification.

This invention relates to gloves.

This invention has utility in hand coverings wherein one material may provide a 10 lining and a second material may provide a wear facing for such lining more particularly at exposed portions for resisting impairment by usage while the hand covering may retain a condition for ready flexing and 15 still be of a type for economical cutting and assembly.

Referring to the drawings:

Fig. 1 is a view of the palm side of a 20 type of glove in accordance with the invention herein;

Fig. 2 is a back view of the glove of Fig. 1;

Fig. 3 is a view of the palm side of the 25 glove of Fig. 1, the glove being turned inside out;

Fig. 4 is a view of the inside of the back of the glove of Fig. 1;

Fig. 5 is a blank for the lining of the 30 glove front;

Fig. 6 is a blank for the thumb back lining;

Fig. 7 is a blank for the second finger back lining;

Fig. 8 is a blank for the third finger back lining;

Fig. 9 is a blank for the little finger back lining;

Fig. 10 is a blank for the facing of the glove front;

Fig. 11 is a blank for the thumb back 40 facing;

Fig. 12 is a blank for the index finger back facing;

Fig. 13 is a blank for the second finger back facing;

Fig. 14 is a blank for the third finger back facing; and

Fig. 15 is a blank for the little finger back facing.

The lining may be of canton flannel, the 50 facing of leather, and the gauntlet of duck, canvas or buckram, when a cheap glove for hard service is sought. For driving gloves, or other purposes where appearance is sought or special purposes, special and 55 higher characters of material may be used.

As herein disclosed the glove of this invention is formed of lining members and facing members, the lining members covering the front and back of the hand including the fronts and backs of the fingers, but not being 60 of sufficient extent in the finger portions to meet around the fingers so as to fully inclose the same.

The lining blank as herein disclosed comprises a palm portion 1, having inside thumb portion 2 integral therewith. The cut out of this thumb portion 2 tends to define index finger back portion 3 adjoining index finger front portion 4. Digit defining cuts toward the palm 1, separate lining portions 5, 6, 7, 70 respectively for the second, third and little finger front sides.

Instead of a back integral with the front, for the lining, there is shown herein separate linings for the backs of the digits, except as 75 for the index finger. The front lining blank in its configuration away from dotted line 8, and short thereof, shows a saving in stock in cutting this palm lining. The spacing of the digit linings 5, 6, from those adjoining, increases the waste, which has a value, but this spacing has as its main purpose simplifying the seaming or assembly operations. This preservation of lining utility as a soft 80 protective surface in coating with the skin of the wearer's hand, and still keeping the more harsh wear facing against direct rubbing with such skin, especially in usage thrusts, is maintained, and with a still further degree of economy in cutting the back 85 lining digits, also with a simplification of the seaming or assembly operations.

Thumb back lining 9 in departing from full thumb back form for full marginal seaming of dotted lines 10, 11, directly brings about a considerable saving in material cost. Second finger lining 12, in its departure from full lining seaming dimension, permits a saving of material as indicated by the difference between the blank outline 12 and 95 the dotted lines 13, 14. Similarly for third finger back lining 15, there is material saving as shown by the dotted lines 16, 17; and for little finger back lining 18, there is the saving indicated by lines 19, 20.

Palm facing 21 has integral therewith thumb inner side 22, also portion 23 as a facing fourchette alongside index finger facing 24. Adjoining are digit facings 25, 26, 27, respectively for second, third and 100 110 little finger.

- little fingers. This inner side of the hand facing is of full size for seaming. Thumb back facing blank 28 has cut or slit 29 from just short of its tip, to permit spreading thereof to an outer seaming size approximated by the lines 30, 31, shown as dotted. This makes the backing of a fourchette type. Fourchette or fractional back facing 32 for the index finger is short of full index finger backing as indicated by dotted line 33. Second finger back facing 34 is provided with cut or slit 35 to adjacent its tip portion for spreading in assembly to approximate outer dimensions for seaming as indicated by dotted lines 36, 37.
- Third finger back facing blank (Fig. 14) 38, has cut or slit 39 from adjacent the tip to permit spreading to approximate assembly dimension indicated by dotted lines 40, 41.
- 20 Little finger back facing blank 42 (Fig. 15) has cut or slit 43 from adjacent its tip to permit spreading to approximate assembly dimension indicated by dotted lines 44, 45. The full lines in Figs. 5 to 9 inclusive and Fig. 12, represent the actual blanks applicant uses, whereas the dotted lines represent the extent the blanks would have to be enlarged if they were to meet around the fingers so as to fully enclose the same. Figs. 11, 13, 14, 15, represent the blanks as cut, whereas the dotted lines represent marginally the extent of the spreading of the blanks for effective assembly.
- In assembly V-seams 46 up the cloth digit backs or linings serve to expose such lining through the spread cuts or slits of the back facings or fourchettes in assembling such separate fourchettes with the finger backs, all herein being of extent from the glove wrist portion. Back seams 47 are then run from the wrist portion to the finger crotches, and the glove is flat assembled open. Wrongside or lining side out may be the folding of such developed assembly, and for the right hand glove, it is preferable to start closing seam 48 at the wrist from the little finger up over the little finger, down to the forward side of the crotch between the little finger and third finger with full leather or facing seaming with the front edges of the fourchettes to the palm facing unit and its digits. In this seam 48, the digit front linings essentially need only be tacked to maintain a desired wear position, such tacking preferably occurring at the tip portion of the digits. Corners 49 of the back digit linings may be tacked by the back seams 47 adjacent, but preferably not in the crotches. While the back linings may be additionally tacked by the seam 48 at the finger tips, such tacking by the closing seam is not essential, for the V-seams 46 are of sufficient extent to maintain the back linings in place, the extent of such digit strips wristward from the crotches between

the fingers being for a full lining facing for the hand back, notwithstanding such lining digits are not directly assembled in the fourchette uniting seams 47. For left hand glove assembly, it is preferable to start the closing seam 48 at the index finger tip and run to the little finger outer side base portion wristward. Before either closing in operation, seam 50 assembles the thumb fourchette with the thumb inner facing, and in wristward extent from the thumb may effect tacking of the lining therewith.

The glove as thus assembled is fully protected at all wear portions, is reinforced to the wrist in the back. By wrist seam 51 gauntlet 52 with supplemental wear facing 53 below the second finger region, a wearer's sleeve or garments from the hand may be protected. The digit backs, as opened into fourchette form, leave single thickness of the more flexible lining, as compared with facing or facing and lining, at the back portions as flexed over the knuckles and joints. There is thus retained in this glove the maximum of facing strength, with elimination of facing resistance to flexing. This is a feature of ease in glove use. All seams along the finger regions of flexing are but two thickness assembly seams. There is thus a minimum tendency to finger spreading in use, with fatigue therefrom.

Single pair of material edges assembled through the crotch regions between the fingers simplifies sewing operation, as well as eliminates hard packed regions resisting turning of the gloves assembled lining side out to the facing side out for sale and use. The assembly operation costs due to keeping the lining clear of the finger crotch seams, as to seaming, amounts to 10¢ per dozen pairs of gloves, even on the cheaper gloves of the so-called canvas work type, when provided with a wear facing.

The greater factors of economy herein reside in material savings. On a No. 10½ glove cut for a full seamed lining approximately 280 yds. of cloth is required. Cutting for such size glove a lining according to the blanks herein disclosed for cloth saving, such may be accomplished with 200 yds. of material. This is a straight saving of 80 yds. or nearly 30%, and in the production of a better article—fully lined as to the feeling of the skin of the hand, more flexible, not waddly or bungling, and of really superior wearing quality for the same grade of stock, for great difficulty is experienced in assembling more than two materials at one seam to have all straight and no local strain placed upon one to weaken such by distortion as to the others.

In the particular example of the canton flannel lined glove of leather facing for rough work uses, with these cheaper mate-

rials, the reduction in costs to be effected are less, and also the margins for sale are also closer. The straight yardage of the lining is such as to be simply computed.

5 With leather for the facing, the various shapes of the skins involve many factors. However, the smaller cuts as herein over the full sizes, mean that portions which might otherwise be scrap are conserved for 10 use. Apart from this economy, on an area basis, there is a saving approximately 6 sq. ft. of leather on each dozen pairs of No. 10½ gloves as faced hereunder, over a full facing. Every working seam herein as uniting facing material, is a leather to leather seam of such facing material. There is a minimum of thread in a compact tight seam. The only facing leather to cloth lining 15 seams of the hand portion are those of the back, which are flat sewed, and so remain— instead of being spread as are the others. These flat seams 20 are not in severe usage exposure regions, and as flat, maintain a maximum of strength. Furthermore, as 25 spaced from the lining edges, there is no tendency to fray to weaken such seams.

What is claimed and it is desired to secure by Letters Patent is:

1. A glove having a finger back blank of 30 one element marginally narrowed short of finger closing width, and a second element also marginally narrowed short of finger closing width, said elements each being of extent from finger tip across the back of the 35 hand portion, said second element being

centrally longitudinally cut for a portion of its length to permit opening of said cut portion to finger closing width, and means for mounting the first element to close said opening in the second element. 40

2. A glove fourchette of extent from finger tip to wrist back, said fourchette being narrowed short of finger width and cut from adjacent the tip wristward to spread to full finger back width. 45

3. A glove having palm and finger front facing continuous from the palm, fourchette facing completing finger crotches with said front and palm facing, a back lining carried by the fourchette facing, and a front lining 50 independent of the back lining throughout the finger extent, said linings being directly tacked together at the finger tip region.

4. A glove having a back comprising a lining of extent from finger tip across the 55 back of the hand portion of the glove and narrower than the finger back width, a facing of extent from finger tip across the back of the hand portion of the glove and narrower than the finger back width, such facing being centrally cut from short of the finger tip to open its full length wristward therefrom, and stitching uniting said opened portion of the facing marginally of the lining so as to fill in said opening for thereby 60 producing a full finger back for margin facing assembly into a glove. 65

In witness whereof I affix my signature.

HERMAN GILLIAN.
